(57) **CLAIM**

The ornamental design for a face mask, as shown and described.

DESCRIPTION

FIG. 1 is a front perspective view of a face mask;
FIG. 2 is a front view of the face mask thereof;
FIG. 3 is a back view of the face mask thereof;
FIG. 4 is a left side view of the face mask thereof;
FIG. 5 is a right side view of the face mask thereof;
FIG. 6 is a top view of the face mask thereof; and
FIG. 7 is a bottom view of the face mask thereof.
The face mask of the present invention is used by a user for
facial skincare.
